United States Patent Office

Des. 194,195
Patented Dec. 4, 1962

194,195

CONTROL PANEL FOR A TELEVISION RECEIVER OR SIMILAR ARTICLE

James W. Kelso, Pacific Palisades, Calif., assignor to Packard-Bell Electronics Corporation, Los Angeles, Calif., a corporation of California

Filed Oct. 24, 1961, Ser. No. 67,245

Term of patent 14 years

(Cl. D56—4)

FIGURE 1 is a front perspective view of a control panel for a television receiver or similar article, showing my new design with a television cabinet being shown in broken lines for illustrative purposes only;

FIGURE 2 is an enlarged perspective view;

FIGURE 3 is an enlarged front elevational view;

FIGURE 4 is an enlarged side elevational view; and

FIGURE 5 is an enlarged and elevational view thereof, looking from the top of FIG. 3.

I claim:

The ornamental design for a control panel for a television receiver or similar article as shown and described.
